UNITED STATES PATENT OFFICE.

CHARLES A. SCHNELL, OF WALTON, KANSAS, ASSIGNOR OF ONE-HALF TO JOHN H. EBERHARD AND HARRY MELLOR, BOTH OF BUTLER COUNTY, KANSAS.

GRAIN-DOOR FASTENER.

1,405,013.

Specification of Letters Patent. Patented Jan. 31, 1922.

Application filed July 27, 1920. Serial No. 399,260.

To all whom it may concern:

Be it known that I, CHARLES A. SCHNELL, a citizen of the United States, residing at Walton, in the county of Harvey and State 5 of Kansas, have invented certain new and useful Improvements in Grain-Door Fasteners; and I do hereby declare the following to be a full, clear, and exact description of the invention, such as will enable others 10 skilled in the art to which it appertains to make and use the same.

The object of the invention is to provide a relatively simple and efficient means for securing a grain door in a car, said means 15 being of such construction as to be readily applicable to cars already in use and serving to effectively retain the door in such relation to the opening as to prevent the escape of the grain while permitting of the 20 ready securing and removal of the door when required; and with these objects in view the invention consists in a construction and combination of parts of which a preferred embodiment is shown in the accompanying drawing, in which—

Figure 1 is an elevation of the apparatus and a portion of the door secured thereby, viewing the same from the inside of the car.

Figure 2 is a vertical sectional view of 30 the door on the plane indicated by the line 2—2 of Figure 1 showing the fastening or holding apparatus embodying the invention in elevation.

Figure 3 is a sectional view of the door fastener showing the usually permanent or fixed door post in elevation.

Figure 4 is a detail view in section of the 40 foot block and attached plate showing the lower ends of the door post and grain post in operative relation therewith.

Figure 5 is a detail view in perspective of the foot plate detached.

Figure 6 is a similar view of a slightly 45 modified form of foot plate when it is desired to apply the attachment to a car without removing the door post.

Figure 7 is a detail sectional view illustrating a swivel spool mounted onto a clamping bolt.

50 The door post 10 usually forms a part of the structure of a car and serves as a bearing for the outer surface of a grain door 11 which may consist of a plurality of superposed planks of which in the construction illustrated the extremities are interposed be-

tween the inner surfaces of said door post and the grain posts 12 which are supported in parallelism with the door posts and are provided with means for securing the sections of the door in their proper relations with the door post.

Engaged with the lower end of each door post is a foot block 13 having at its outer end a notch 14 for the reception of the lower end of the door post, and carried by the foot 65 block is a foot plate 15 having a flanged opening 16 for embracing the door post, said plate being effectively bolted as indicated at 18 to the foot block. In the modified construction illustrated in Figure 6 the flanged 70 opening in the foot plate is open at its outer end to permit it to be fitted to a stationary door post or applied thereto without removing said post, the open side of the said opening being closed by a clamp plate 18 held in 75 place by threaded stems 19 and engaged by nuts 20. The foot plate is provided with a seat 21 for the lower end of the grain post 11 and a bolt 22 mortised into the lower end of the grain post extends downward through 80 the plate and the foot block and is engaged below the lower surface of the latter by a nut 23 while the upper end of the grain post is provided with a bracket arm 24 extending 85 toward and bearing against the inner surface of the door post and slotted as shown at 25 for the reception of a securing bolt 26. The slot permits of a variation in the dimensions of the parts in the application 90 of the attachment to different cars without the necessity of special operation in the matter of fitting.

The grain post is preferably metallic and may be intermediately cut away or slotted as shown at 26' to lighten the same without 95 materially affecting its strength, and threaded in the grain post are clamping bolts 27 provided at their outer ends with swiveled spools 28' for bearing contact with the surfaces of the door sections or members, said 100 spools being fitted upon reduced terminals 28 of the clamping bolts and being held from displacement by transverse cotter pins 29. The spools are preferably provided with reduced biting edges 30 for impressing the surface of the door so as to firmly engage the same and prevent displacement by jarring or otherwise.

It will be seen that the apparatus may be 110 readily erected in a grain car of the ordi-

nary construction as now used, and will serve as an efficient means for securing the door therein against displacement either outwardly or inwardly or longitudinally of the 5 car and hence will guard against the wastage incident to the loosening of the doors of grain cars while in transit, and at the same time it will be seen that the attachment may be applied to a car at a moderate cost and 10 may be used successively upon different cars if desired, the removal thereof not involving any mutilation of the car or such a damage thereto as will render the same unfit for further use.

15 Having thus described the invention, what I claim is:—

1. A door fastener for grain cars having a grain post carrying means for engaging grain door sections or members and adapted 20 for arrangement in parallelism with a car door post, a foot block provided at its outer end with a notch for receiving the lower end of the car door post, a foot plate carried by the foot block and having a flanged 25 opening for the reception of the car door post and a seat for the lower end of the grain post, and means for securing the lower end of the grain post in said seat and for securing the upper end of the grain post 30 to the car door post.

2. A grain door fastener for cars having a grain post for arrangement in parallelism with the grain car door post and provided at its lower end with a foot block, means 35 for securing the upper end of the grain post to the car door post, means for securing said foot block to the lower end of the car door post, and door locking devices carried by the grain post and consisting of bolts 40 threaded in said post and provided at their outer extremities in the interval between the grain post and the car door post with swiveled spools having biting edges for engagement with the surfaces of the grain 45 door sections or members.

3. A door fastener for grain cars comprising a foot plate secured to the floor of the car and extending inwardly from the door post thereof, and provided at a distance inwardly of said post with a seat, a grain post having its lower end positioned in said seat, means to secure the upper end of said grain post to said door post, and door engaging means carried by said grain post, said means comprising a series of independently adjustable clamps. 50

4. A door fastener for grain cars having a grain post for arrangement in parallelism with the car door post, a foot plate for engagement with the grain and car door posts, 60 whereby their lower extremities are held in spaced relation, the grain post having its upper end bent to engage the inner face of the car door post and being provided with a slot, securing means passing through said 65 slot and engaging said door post, and clamping means carried by the grain post for engagement with the door for holding it against accidental displacement.

5. A door fastener for grain cars including a door post, a grain post arranged in parallel relation thereto, a foot plate having seats for the reception of the lower ends of said posts, means for securing the upper ends of the posts together, and door clamps 75 carried by the grain posts.

6. A door fastener for grain cars including a door post, a grain post arranged in parallel relation thereto, a foot plate having seats for the reception of the lower ends of 80 said posts, means securing said plate to the floor of the car, means securing the upper ends of the door posts together, and door clamps carried by the grain posts.

In testimony whereof I affix my signature 85 in presence of two witnesses.

CHARLES A. SCHNELL.
